SILAS A. STRICKLAND, OF DETROIT, MICHIGAN

METHOD OF MAKING VALVE SEAT RINGS

Application filed March 14, 1932. Serial No. 598,719.

This invention relates to methods of making renewable valve seat rings used particularly in internal combustion engines.

Renewable valve seat rings, as used in internal combustion engines, are often made of a high grade metal, one which resists pitting and corrosion, and because such metals are relatively expensive and hard to machine, the rings are also relatively costly. Sometimes in order to reduce costs, lower grade material such as cast iron, is used for the rings, but without satisfaction for cast iron does not resist pitting and corrosion effectively.

It therefore appears desirable to provide a novel method of making such rings, a method which will be so economical as to permit the use of high grade and expensive materials, in competition to cheaper materials. The novel method reduces costs by eliminating waste and expensive machining in the formation of the blanks from which the ring may be made, and is the principal object of the invention.

In making valve seat rings, by the method of the invention, it is first contemplated to make a ring blank, so shaped and dimensioned, as to require no machining or processing, other than finish-grinding, in order for it to be transformed into a completely finished valve seat ring. Various methods of making such blanks may be suggested, but all heretofore known, require considerable machining and cause great waste of the material employed. In the method of the invention, wherein arcuate pieces are first formed, and are then joined in a manner to form a ring of the proper shape and dimensions, very little machining is required and but little waste is caused.

The invention will be readily understood by those skilled in the art upon reference to the following description and the accompanying drawing in which,

Figure 1 shows a straight elongated blank element, from a plurality of which a ring blank may be made;

Fig. 2 shows the element of Fig. 1 in an intermediate stage of manufacture; the upper portion of this figure is a top plan view

of the element and the lower portion is a cross section of the same on the line 2—2.

Fig. 3 shows two elements of the form of Fig. 2 placed in juxtaposition and ready for joining;

Fig. 4 shows two elements joined;

Fig. 5 shows in cross section and in top plan view a valve seat ring blank; and

Fig. 6 shows, in cross section, a finished valve seat ring in use in an internal combustion engine.

In making the ring blank, a plurality of blank elements are joined to form a ring. These elements may be cut from a coil of the material, or from straight lengths of the same. The nature of the supply stock, in this respect, is immaterial. It is preferred, and considered desirable, to have the stock of the cross section of the ring blank, in order to eliminate the necessity of machining or otherwise processing the blank elements during their manufacture.

In Fig. 1, the blank element 10 is shown in the form of a straight length, having a cross section like that of the ring blank and having a length slightly greater than that of one half the ring blank. Two of these blank elements are used, and their aggregate length is slightly greater than the circumference of the ring blank.

In the method of the invention the blank element 10 is first formed into an arc of the radius R. This radius being equal to that of the ring blank. Since the blank element 10 is more than a semi-circle in length, ends 12 thereof will project beyond the diametrical line 2—2 traversing the blank element.

Two elements of the form of Fig. 2 are then placed in juxtaposition, as in Fig. 3, and are then joined, preferably by welding, to form the ring of Fig. 4. While the elements are being welded to each other, they are moved towards each other so as to lessen their aggregate length and to make the same equal to the circumference of the ring blank, thus causing the latter to become a perfect circle, with a diameter equal to $2R$, the desired diameter.

The surplus metal, indicated at X, is then

trimmed off, in any suitable manner, to form a ring blank, from which a finished valve seat ring may be made, merely by grinding to size.

5 While the drawing shows two blank elements, each in the form of a semi-circle, joined to form a ring blank, it will be understood that three or more arcuate blank elements may be used. The aggregate length 10 of the elements being used should be slightly greater than the desired circumference of the ring blank, the cross section of the elements should be the same as that of ring blank, and the radii of the arcs of the elements should be the same as that of the ring blank.

It will be seen that there is substantially no waste of metal, no expensive and laborious machining and very little grinding necessary when ring blanks are made by the method of the invention. It will further be seen that a ring blank made by the method of the invention, though initially of separate pieces, is in its finished form a 25 one piece or integral article of manufacture and structurally does not differ from ring blanks made by other methods.

It will further be seen that due to the elimination of waste, expensive machining operations, etc., a ring blank can be made by the method of invention at a far lower cost than is possible with other methods of manufacture.

Now having described the invention it is 35 to be understood that the same is to be limited, not to the specific method herein set forth, but only by the scope of the appended claim which follows:

What I claim is:—

40 In the production of renewable valve seats from high grade material with minimum wastage of material, the method which consists in providing one of the seat structural dimensions by preparing the stock with a 45 cross-section substantially corresponding to the cross-section of the seat, producing from the stock a plurality of arcuate embryo elements each having the radius of the arc corresponding to the finished radius of the seat 50 with the length of the element greater than the lengths of a segment of the proper arcuate length of the element in the complete seat to be formed while maintaining the constancy of such cross-section, assembling 55 the required elements end to end to produce an embryo assembly in which the circular contour has a deformed appearance as compared to the finished seat, welding the assembled elements at the respective end zones 60 of the elements with the flash internal and external to reduce the arcuate length of the elements to the desired length, and removing the flash to complete the dimensional characteristics of the seat blank, whereby the 65 cross-section of the seat is completed in ad-

vance of fashioning the seat annular contour and thereby permit the cross-section of the seat to be determined by the production of the stock.

In testimony whereof I affix my signature.

SILAS A. STRICKLAND.
